TOOTHBRUSH

Gary R. Greenfield, East Rockaway, N.Y., assignor to Groomaid International, Ltd., Merrick, N.Y., a corporation of New York

Filed July 12, 1968, Ser. No. 12,724

Term of patent 14 years

Int. Cl. D4—02

U.S. Cl. D4—18

FIG. 1 is a perspective view of the toothbrush showing my new design with the sliding protector tube in the closed position.

FIG. 2 is a view of the right side of FIG. 1.

FIG. 3 is a view of the left side, and

FIG. 4 is a perspective view of the toothbrush with the sliding protector tube in the open position and the left side end cap shown separately for complete disclosure.

I claim:

The ornamental design for a toothbrush, substantially as shown and described.
